US00D825096S

(12) **United States Design Patent** (10) Patent No.: **US D825,096 S**
(45) Date of Patent: ** Aug. 7, 2018

(54) **HORTICULTURE GROW LIGHT**

- (71) Applicant: **IP Holdings, LLC**, Vancouver, WA (US)
(72) Inventor: **Christopher Reynolds**, Vancouver, WA (US)
(73) Assignee: **HGCI, Inc.**, Las Vegas, NV (US)
(**) Term: **15 Years**
(21) Appl. No.: **29/621,534**
(22) Filed: **Oct. 9, 2017**

Related U.S. Application Data

- (63) Continuation of application No. 29/596,812, filed on Mar. 10, 2017, now Pat. No. Des. 802,831, which is a continuation of application No. 29/578,892, filed on Sep. 26, 2016, now Pat. No. Des. 786,491, which is a continuation of application No. 29/538,398, filed on Sep. 3, 2015, now Pat. No. Des. 770,671.

(57) **CLAIM**

The ornamental design for a horticulture grow light, as shown and described.

DESCRIPTION

FIG. 1 is a perspective view of a horticulture grow light, as viewed from below, showing my new design; FIG. 2 is a perspective view of the light shown in FIG. 1, as viewed from above; FIG. 3 is a left side view of the light shown in FIG. 1; FIG. 4 is a right side view of the light shown in FIG. 1; FIG. 5 is a front elevation view of the light shown in FIG. 1; FIG. 6 is a rear elevation view of the light shown in FIG. 1; FIG. 7 is a bottom plan view of the light shown in FIG. 1; and, FIG. 8 is a top plan view of the light shown in FIG. 1; The broken-line disclosure shown in the views is understood to represent portions of the article in which the claimed design is embodied, but which form no part of the claimed design.
